UNITED STATES PATENT OFFICE.

WILLIAM GEORGE MOORE, OF MIAMI, FLORIDA.

DESIGN FOR A TWO-WHEELED AUTOVEHICLE.

50,280.

Specification for Design.

Patented Feb. 6, 1917.

Application filed February 2, 1916. Serial No. 75,855. Term of patent 7 years.

To all whom it may concern:

Be it known that I, WILLIAM GEORGE MOORE, a citizen of the United States, residing at Miami, in the county of Dade and the State of Florida, have invented a new, original, and ornamental Design for Two-Wheeled Autovehicles, of which the following is a specification, reference being had to the accompanying drawing, forming part hereof.

The figure is a side elevation of a two wheeled autovehicle built according to my new design.

I claim:

The ornamental design for a two-wheeled autovehicle, as shown.

WILLIAM GEORGE MOORE.

Witnesses:

A. B. CRUMP,
G. D. BROSSIER.
